TICKET MANIPULATING MACHINE

James Sinclair Arcus, Sr., Lombard, Ill., assignor to The Arcus Ticket Co., Chicago, Ill., a corporation of Illinois

Application September 25, 1953, Serial No. 382,244

12 Claims. (Cl. 101—19)

This invention relates to an improved ticket manipulating machine such as disclosed in co-pending application for patent Ser. No. 289,911 filed May 24, 1952.

As set forth in the application for patent referred to, in the entertainment field, such as sporting events, including horse racing metes, and the like, it has been conventional to issue passes to a number of groups of attendants. Record of the use of such passes for each day of each mete has been required for a number of reasons, as an instance, to provide against misuse of the passes by unauthorized persons, to prevent use of a single pass for more than one admission, thereby in turn to detect whether such pass had been transferred to an unauthorized person to gain admission after the authorized user had been admitted, and to determine a list of the passes which are taxable and those which are not taxable.

In the aforesaid patent application, it was sought to achieve the result by a manually operated mechanism. With a view to simplifying that construction and reducing the mechanism to a minimum, the present invention aims to provide an improved ticket manipulating machine relying upon electric motive power in which a ticket, such as disclosed in the aforesaid patent application, constitutes the pass for use with such machine, (1) whereby the authorized passes can be readily detected both as to the mete and as to the date of the mete, (2) whereby an unauthorized repeat use of an authorized pass can be readily detected, that is, whereby all passes previously used for the day of the mete can quickly be detected and rejected if wrongfully presented for a second admission, (3) whereby a record of the authorized passes presented for a single day of a mete can be effected and retained with the machine, (4) whereby a record can be effected on the pass itself to indicate that it has been used for the day of the mete, and (5) whereby one and the same pass can be used once for each of a number of different days of a particular mete, depending upon the setting of the machine.

Still furthermore, the present invention aims to provide an improved electrically operated ticket manipulating machine for use with a ticket such as disclosed in the aforesaid patent application constituting a pass for use with such machine, which ticket has a first predetermined structural conformation thereon to correspond to the setting of the machine for a particular mete, a second structural conformation thereon to correspond to the setting of the machine for a particular day of the mete, and a third structural conformation thereon to cooperate with the machine to record such third conformation to be retained with the machine, and the machine (1) is provided with a first detecting means to cooperate with the first structural conformation on such pass to detect passes authorized for the mete, (2) is provided with a second detecting means to cooperate with the second structural conformation on the pass to detect passes authorized for the particular day of the mete, (3) is provided with a first record producing device for marking the authorized passes presented, (4) is provided with a second record producing

2

device cooperating with the third structural conformation on the pass to reproduce the same or record it for retention with the machine, (5) in which the second detecting means can be changed at the end of a day to serve for another day of the mete and to cooperate with the second structural conformation of an authorized pass which may or may not have been used for a previous day of the mete, and (6) in which the first detecting means of the machine can be changed for use with another mete to cooperate with the first predetermined structural conformation of the passes which have been conformed to correspond to such other mete.

Still furthermore, the present invention aims to provide an electrically operated ticket manipulating machine in which the ticket, such as disclosed in the aforesaid patent application, when received by the machine, if an acceptable ticket, at the beginning of a cycle (1) will actuate an electric switch to establish the circuit for an electric motor as a result of which the mechanism operatively connected with the motor will (2) complete the advance of the paper on which a record is to be printed (3) upon completing the advance of the paper, initiating the advance of a counter, (4) actuate a switch lock to retain the switch in closed position and in turn release the switch lock to restore the switch to open position, (5) at substantially the same time actuate a printing mechanism and subsequently restore the printing mechanism to initial at rest position, also (6) at substantially the same time initiate the actuation of a punch to perforate or mar the structural appearance of the ticket, complete such marring action and thereupon restore the punch to its at rest position upon the completion of the cycle, (7) complete the actuation of the counter after initiating the actuation of the punch, and (8) thereupon initiating the advance of the paper before releasing the switch lock and restoring the printing platen and punch to inoperative position at the end of the cycle, leaving the completion of the advance of the paper for the beginning of a succeeding cycle.

These and other features, capabilities and advantages of the present invention will appear from the subjoined detailed description of one specific embodiment thereof illustrated in the accompanying drawings, in which

Fig. 1 is a side elevation partly in section showing the two main frames separated from one another.

Fig. 2 is a front view of the machine.

Fig. 3 is a section on the line 3—3 of Fig. 2 showing the punch in restored position.

Fig. 4 is a section on the line 4—4 of Fig. 3.

Fig. 5 is a section similar to Fig. 3 showing the punch in projected position.

Fig. 6 is a fragmental plan view of the machine showing an acceptable ticket in position.

Fig. 7 is a section on the line 7—7 of Fig. 6.

Fig. 8 is a section on the line 8—8 of Fig. 2.

Fig. 9 is a fragmental detail of a part of the mechanism shown in Fig. 8 with the cam in a different position.

Fig. 10 is a section on the line 10—10 of Fig. 6.

Fig. 11 is a section on the line 11—11 of Fig. 3.

Fig. 12 is a section on the line 12—12 of Fig. 2.

Fig. 13 is a section on the line 13—13 of Fig. 1.

Fig. 14 is a fragmental section on the line 14—14 of Fig. 2 illustrating the relationship of one of the cams and cam rollers in the position shown in Fig. 3.

Fig. 15 is a fragmental section on the line 8—8 of Fig. 2 and shows the relationship of another of the cams and cam rollers in the position shown in Fig. 3.

Fig. 16 is a section similar to Fig. 14 showing the cam in a different position.

Fig. 17 is a plan view of the ticket shown in Fig. 6 removed from the machine.

Fig. 18 is a fragmental view of the record strip.

Fig. 19 is a detached perspective of a part of the switch actuating device.

Figs. 20 and 21 are perspective views of a pair of attachments for the ticket receiving frame.

Figs. 22 and 23 are perspective views of another embodiment of the attachments shown in Figs. 20 and 21, respectively.

Fig. 24 is a perspective of a third embodiment of the attachment shown in Fig. 21.

Fig. 25 is a diagram or chart showing the several operations of the machine in relation to one another.

The operation of the machine when inserting a pass, detecting an authorized pass, producing a record on the pass so presented to indicate that it has been used for a day of a month and for producing a record for retention with the machine, for convenience of description may be assumed to take place during a single cycle of operation. However, since the aforesaid functions performed by the machine, as well as others, overlap, the sequence of these several functions may vary, the functions themselves may vary, and the mechanical and electrical expedients for carrying out these several functions may vary, and some may actually be omitted without departing from the general spirit of the invention. The order in which the several mechanical and electrical expedients illustrated will be described is not intended to delineate their importance nor the preferred sequence, but is arbitrarily determined with a view to facilitating the description.

In a general way, the invention contemplates the use of a pass or ticket having data formed thereon in raised characters, the introduction of the pass into cooperation with a mechanism in the machine which will cooperate with the contour of the pass electrically to condition the machine for operation if it is an authorized pass, and the then ensuing actuation of the machine first to complete the advance of the record strip, paper as an instance, with the impression creating medium, such as a strip of carbon paper, thereupon initiating the actuation of a counter mechanism when used, thereupon actuating a lock to anchor the switch in closed position, and at about the same time after completion of the advance of the record strip, actuating the printing platen for an instantaneous printing impression and clearing the ticket for operation by the punch, thereupon initiating the actuation of the punch to change a part of the contour of the ticket to form a record on the same indicating that it has been used, thereupon completing the actuation of the counter, thereupon completing the punching operation and initiating the withdrawal of the punch and at the same time initiating the advance of the record strip, thereupon upon the completion of the cycle completing the restoration of the punch and printing platen to neutral position, and releasing the switch lock, and finally withdrawing the ticket from its impression producing relation with the printing platen.

The main frame

The main frame consists essentially of a housing 1 having a top plate 2 resting on the upper edges of the same and secured to such upper edges. To this top plate 2 there is secured the main frame 3 having the transversely extending base plate or casting 4 from which extend four hangers, to wit, the front hangers 5 and the rear hangers 6, which are secured at their upper ends to the supporting plate 2. On the base plate or casting 4 adjacent the outer ends thereof, there are formed two raised runways 7 and 8 on which are slidably supported the cheek plates 9 and 10, respectively, of the auxiliary frame 11 which is connected at its front end by the cross bar 12 and a plurality of cross rods 13, 14, 15 and 16.

The main drive now to be described is mounted on the main frame 3.

The main drive

Secured to the base plate 4 and suspended therefrom

is the motor 17 which has drivingly connected thereto the sprocket wheel 18, which in turn is connected by the sprocket chain 19 to the sprocket wheel 20 fixed on the stub shaft 21 extending through one of the hangers 5 above the base plate 4 on the right hand side of the machine. This stub shaft 21 is journaled in one of the hangers 5 in alinement with the stub shaft 22 journaled in the other hanger 5 disposed on the left hand side of the machine. The stub shafts 21 and 22 have secured thereon between the two hangers 5 the eccentric 23. Between the eccentric 23 and the hanger 5 on the right hand side of the machine, there is fixedly secured the cam 24. In turn, between the eccentric 23 and the hanger 5 on the left hand side of the machine, there are disposed two cams 25 and 26, the cam 25 in the present instance being disposed between the eccentric 23 and the cam 26, and the cam 26 being disposed between the hanger 5 and the cam 25. To the left of the hanger 5 on the left hand side of the machine, there is fixedly mounted on the stub shaft 22 the eccentric 27.

To the outer face of the hanger 5 on the right hand side of the machine near the upper end thereof is secured the microswitch 28 having a downwardly extending projection 29 for engagement by the arm 30 having a roller 31 at its free end for engagement by the cam bracket 32 mounted on the shaft 33 extending through the two hangers 5, the cam bracket 32 having two cam faces, one 231 projecting relative to the other 232. The shaft 33 in the present instance has fixed thereto the short arms 34 which have fixed at their outer ends the cross rod 35. The shaft 33 in addition has secured thereto the arm 36 which has a pin 37 riding in the slot 38 of the link 39 connected at its lower end to the lever 40 pivotally connected at 41 to the hanger 5 at the left hand side of the machine, which lever 40 has a cam roller 42 thereon maintained in engagement with the periphery of the cam roller 26 by means of the spring 43 connecting the pin 44 at the very end of the lever 40 to the abutment 45 on the base plate 4. For normally maintaining the pin 37 of the arm 36 in engagement with the lower end of the slot 38, there is provided the spring 46 connected at one end to the pin 37 and at the other end to the abutment 47 fixed on the link 39. The cam 32 as aforesaid is fixed to the shaft 33. Consequently when the cross rod 35 is actuated to rock the shaft 33, it in turn will actuate the cam 32 to actuate the arm 30 to engage and actuate the projection 29 of the microswitch 28 and close the same. The cam 26 in cooperation with the lever 40, link 39 and arm 36, will maintain the cross rod 35 in actuated position during the operation of the machine so that if once actuated the cross rod 35 will remain in actuated position until a complete cycle of the machine has been completed.

55 The microswitch 28 is connected to the motor 17 so that when the road 35 is actuated the circuit to the motor 17 will be established and the current to the motor not interrupted until the projection 29 is again released, the cam 26, however, as aforesaid maintaining the cross rod 35 in actuated position and therefore the switch projection 29 in circuit establishing position of the motor, until a complete cycle of the machine has been completed.

The means for actuating the cross rod 35 will now be described consisting essentially of the ticket or pass 48, see Figs. 6 and 17. Since this actuating means depends upon the conforming of the contour of the ticket to the setting of the machine and to that extent the setting of the machine functions as a selector to select and accept the qualifying ticket, it will be referred to as the selecting mechanism.

The selecting mechanism

In addition to the ticket 48, the selecting mechanism includes a mouth or opening 49 in the supporting plate 2, 75 which mouth 49 is disposed in registration with the

mouth 50 of the punching mechanism 51 hereinafter to be described. Above the mouth 50 of the punching mechanism 51 there is slidably mounted the bar 52 which also constitutes the back of the stationary platen of the printing mechanism hereinafter to be described. This bar 52 in the present instance is slidably supported on the supporting bars 53 secured to the inner faces of the hangers 5. The front ends of the bars 53 have extensions 54 through which extend the set screws 55 which are screw threadedly connected to the bar 52 and by means of the nuts 56 on the set screws 55 engaging the front faces of the projections 54, the bar 52 may be adjusted to achieve a satisfactory printing impression location. To the bar 52, in turn, there is secured a frame 57 having a cross bar 58 constituting the stationary platen at its upper end from which extend downwardly extending side bars 59 and 60. To the rear faces of the bars 59 and 60, see Figs. 6 and 7, there are secured the vertically extending members or plates 61 and 62 to form a throat, the inner portions of which are spaced from the cross bar 58 to form slideways for the ticket 48. At the lower ends of the side bars 59 and 60 there are secured attachments, such as the attachments 63 and 64 of Figs. 20 and 21. The attachment 63, see Fig. 20, has an upwardly extending projection 65 in the present instance, see Fig. 6, positioned in alignment with the slideway or guide formed between the plate 61 and the side bar 59. The attachment 64, see Fig. 6, is shown as secured to the lower end of the bar 60. This attachment has a projection 66 which clears the slideway formed between the bar 60 and the plate 62. These projections 65 and 66 are provided to register with notches formed in the ticket 48. If the ticket is a qualifying ticket, that is, qualifies for the mete of a particular race, see Figs. 6 and 17, the ticket will have notches 67 and 68 formed therein which when inserted into the mouth 49 between the bars 59, 60 and the plates 61, 62, the edge 69 of the ticket 48 being in advance, its notches or recesses 67 and 68 corresponding as they do to the position of the projections 65 and 66 of the attachments 63 and 64 when secured to the bars 59 and 60, see Fig. 6, the advance edge 69 of the ticket 48 will be in position or in condition to engage and actuate the projection 70, see Fig. 19, of the bracket 71, the plate portion 72 of which is slidably mounted in the punch mechanism 51 and has rearwardly extending arms 73, 74 provided with slots 75 to receive the cross rod 35. Consequently, if the advance edge 69 of the ticket 48 is intact, that is, not recessed where it registers with the projection 70 of the bracket 71, it will then be in position, the recesses 67 and 68 clearing the projections 65, 66 to depress the projection 70 constituting the movable obstruction and thereby depress the bracket 71 in turn to actuate the cross rod 35. As soon as the cross rod 35 is so actuated by the ticket 48, it will actuate the cam 32 to actuate the switch button 29 to establish the circuit for the motor 17 to initiate a cycle of operation. Immediately that the current to the motor 17 is established, it will actuate the driving mechanism associated therewith to actuate the cam 26 immediately to actuate the lever 40 and link 39 to maintain the cross rod 35 in the position into which it had been actuated by the ticket 48.

In order to change the contour requirement of a ticket 48, the attachment 63 may be provided with two screw openings 76 and 77 to receive the pin or screw 78. In Fig. 6, the screw 78 is shown as passed through the opening 77 into the side bar 59. If the requirement for the notch 67 would be to locate it spaced from the side edge of the ticket 48, then the screw 78 could be passed through the opening 76 as an instance. Or else, see Fig. 22, instead of the attachment 63, an attachment 79 provided with a slot 80 could be used where any number of locations slightly different from one another could be provided for a correspondingly located recess 67. In place of the attachment 64 similarly for relocating the

recess 68 of the ticket 48, an attachment, such as the attachment 81 having the slot 82 could be provided in which case the screw 83, see Fig. 6, would pass through the slot 82. In turn, obviously with the attachment 79 shown in Fig. 22, the screw 78 would pass through the slot 80. Obviously a set of attachments could be provided in which the spaces adjacent the projections, such as the projection 66 of the attachment 64 and the projection 84 of the attachment 85, would vary relative to one another. The material of the ticket 48 must of course be fairly substantial and rigid so that it will not bend or be deflected when actuatingly engaging the projection 70. While cardboard, fibreboard and the like have been found to give excellent results, obviously the ticket could also be composed of a plastic substance, a metal or the like, without departing from the general spirit of the invention.

Between the recesses 67 and 68 of the ticket 48, a pass or ticket to be acceptable or qualified would ordinarily have no other notches cut in the same or else at least be intact and uninterrupted where the edge 69 registers with the projection 70, see Fig. 19, in order to effect the actuation of the cross rod 35.

On the other hand, if one and the same ticket 48 is to be used as an instance for a number of successive days of a particular mete of a horse racing track, then in order to prevent the ticket or pass being used by unauthorized users, after having been used by the authorized user, means are provided to impair, mar or recess the ticket 48 at the edge 69 where the projection 70 would register with the same so that when the ticket 48 were inserted into the mouth 49, and into the punch mechanism 51, the edge 69 would clear the projection 70 when the other recesses 67 and 68 registered with the projections 65 and 66, respectively, as an instance of the embodiment illustrated in Fig. 6. Then the bracket 71 would not be actuated and of course the switch 28 not closed. In turn, of course, if the recesses 67 and 68 would not register with projections, such as the projections 65 and 66, the advance edge 69 of the ticket 48, even though intact, would not engage and actuate the projection 70 and consequently again the bracket 78 would not be actuated to close the switch 28.

In order to change the contour of the advance edge 69 of the ticket 48, any number of means could be used. Excellent results have been achieved when a punch was used to perforate or recess the ticket during the cycle of operation of the machine. This punch and its associated mechanism will now be described.

The Punch

The punch mechanism 51 is fixed on the cross bar 86, which on the left hand side is slidably mounted in the hanger 5 on the left hand side of the machine, while the hanger 5 on the right hand side of the machine has an opening therethrough through which the cross bar 86 passes. The right hand side of the cross bar 86, see Fig. 2, is provided with teeth 87 along its lower edge to mesh with the teeth 88 of the gear 89 fixed on the shaft 90 which extends through the bracket 91 secured to the outer face of the adjacent hanger 5, and which shaft 90 also extends through the hanger 6 at the rear of the machine. On the end of the shaft 90 protruding from the rear face of the hanger 6, there is fixed the toothed numbering wheel 92. This numbering wheel 92, see Fig. 13, has a plurality of notches 93 between its peripheral teeth disposed adjacent to indications on the rear face of the dial 92. The recesses 93 are provided to cooperate with the projection 94 at the lower end of the pin 95 vertically slideable in the boss 96 extending from the rear face of the adjacent hanger 6. The pin 95 is provided with a collar 97 between which and the boss 96 there is disposed the spring 98 resiliently to maintain the projection 94 seated in one of the recesses 93 of the numbering wheel 92. The indications 99 on the dial or

numbering wheel 92 are provided to aid the operator in locating the punching mechanism 51 according to the location of the recess 100 on the ticket 48, see Fig. 17, to be produced by the punch mechanism 51. In other words, if the ticket 48 or pass is to be authorized for the 28th day of the mete, see Fig. 17, then the dial 92 will be set to correspond to this day. In Fig. 13, the dial 92 is set to position the punch mechanism 51 for the 20th day of a mete.

The punch mechanism, see Figs. 3, 5 and 6, consists essentially of a fixed die plate 101 secured to the cross bar 86 and having a female substantially square die 102 formed therein to receive the male die member 103 at the end of the lever 104 which is pivotally mounted on the bracket 105 also secured to the cross bar 86. The lower end of the lever 104 is bifurcated having the arms 106 and 107 secured to opposite sides of the eccentric 23. The eccentric 23 is so timed, see Fig. 25, that it will initiate the actuation of the male die 103 into the ticket 48 immediately after the cross rod 35 has been anchored in switch locking position. In Fig. 3 the lever 104 is shown in its neutral at rest position while in Fig. 5 it is shown in its final punch provoking position, and before being returned by the eccentric 23 to the neutral position shown in Fig. 3.

In some instances, in addition to providing a pass which will protect the racetrack as an instance from unlawful use of passes, that is, the use of a pass by an unauthorized user after the pass has once been used by an authorized user, it is also desirable to obtain a record of the number of passes that have been received at a particular gate or by a particular machine. For this purpose the counter unit 108 now to be described is provided.

The counter

The counter mechanism 108 is mounted on the rear end of the hanger 6 which is at the left hand side of the machine, the operative mechanism of which is connected by the lever 109 and link 110 to the eccentric 27 mounted on the stub shaft 22, see Figs. 2 and 4. Since the stub shaft 22 will make one revolution in every cycle of the machine and the link 110 is connected to the eccentric 27 secured to the stub shaft 22, the counter unit 108 will register a unit for each cycle of operation to indicate the admission or acceptance of each authorized pass, a cycle of operation corresponding to the acceptance of each authorized pass.

In addition to recording the number of authorized passes that have been accepted by the machine, in some instances it is also desirable to obtain a printed record of other matter. As an instance, at a race track, particularly in the United States, according to convention, there are a number of different kinds of passes, some of which entail the payment of a tax and some of which are tax free. It therefore is desirable to separate the records of taxable passes from the records of non-taxable passes to enable the comptroller to prepare the proper return to the tax authorities. It may also be desirable to keep a record of the number of officials or users of different classes. As an instance, there are some passes to the club house for officials, other passes to the club house for association guests, and then various types of passes to the grand stand, such as a horseman-special. In order to enable the comptroller to segregate and sort the various passes into groups, the printing mechanism now to be described is provided.

The printer

The printer in the present instance consists essentially in providing raised characters, such as the letters "G" and "K" and the number "200" on the ticket 48, see Figs. 6 and 17. These letters and numbers are spaced in columns corresponding to the group to which the ticket belongs. The arrangement of the letters "G," "K," and the number "200" as indicated on the ticket indicates the position of the columns in which these letters and the numbers

will appear for all passes to the club house for official guests of the Gulfstream Race Track of Florida. These letters are raised by any number of methods well known in the industry. If the pass were to the club house for an association guest, the column for the letter "G" and the number might be the same, but the column for the letter "K" would preferably be in another column to indicate that the pass was used by an association guest instead of by an official guest. In turn, instead of the letter "G" and the column of it, a different letter might be provided to designate still another type of official, while instead of the location of the column where the letter "K" appears in Fig. 17, a different location and a different letter would appear in the panel 111 of the ticket 48.

The raised condition of the characters 112 in the panel 111, to wit, the letters "G," "K," and the number "200," is relied upon to reproduce an impression of the same on a record strip.

In the present instance the record strip consists of a strip of paper 113 extending from the roll 114 mounted on the roller 115 fixed on the shaft 116 journalled in the arms 117 and 118, see Figs. 1 and 3, which arms 117 and 118 are connected to one another by the cross rod 119 and pivoted at their upper ends on the cross rod 16 supported in the cheek plates 9 and 10 of the auxiliary frame 11. In the normal position the arms 117 and 118 rest upon the cross rod 120 fixed to the extensions 121 extending rearwardly from the plates 122 which in turn extend forwardly from the cross bar 12. Above the cross rod 119 there is journalled the shaft 123 on which is mounted the spool 124 supporting the roll 125 of carbon paper with the impression producing surface 126 on the inner face of the carbon strip 127. The carbon strip 127 with the impression producing face 126 facing the paper strip 113 passes over the cross rod 16, and then over the cross rod 14 and down under the cross rod 15. The paper strip 113 after leaving the roll 114 engages the outer face of the roll 125 of carbon strip and then engages the impression provoking face 126 of the carbon strip 127 when it reaches the rod 116 and from there on the carbon strip 127 and paper strip 113 continue together over the cross rod 14 and under the cross rod 15, and then over the cross rod 128 and over the roller 129 down past the tie rod 130 to and between the feed rollers 131 and 132 to be pulled by them across the ticket 48 between the cross rods 14 and 15.

The cross rod 128 is fixed and supported in the cheek plates 9 and 10 of the auxiliary frame 11. The shaft 133 of the roller 129 is journalled in the upper arms 134 of the plates 122 and the feed rollers 131 and 132 in turn are fixed on the shafts 135 and 136, respectively, the shaft 135 being journalled in the plate 122 and the shaft 136 being journalled in the ends of the arms 121 slidably mounted in the plates 122 and connected to one another by the cross rod 120. On the ends of the shafts 135 and 136 extending to the left of the left hand plate 122, there are fixed the gears 140 and 141, respectively, maintained in mesh with one another by the springs 142 and 143 extending from the cross rod 120 to the abutments 144 and 145 mounted on the plates 122. The springs 142 and 143 thus not only maintain the gears 140 and 141 in mesh with one another, but also maintain the feed rollers 131 and 132 in feeding engagement with the paper strip 113 and carbon strip 127. The shaft 136 extends beyond the right hand side of the plate 122 at the right and has mounted thereon the ratchet wheel 146, see Fig. 12, for engagement by the pawl 147 journalled on the upper end of the bracket 148 pivotally connected to the link 149 by the pin 150, which link 149 in turn is connected to the lever 151 by the pin 152, which lever 151 is journalled on the shaft 153 and is provided with a cam roller 154 in engagement with the cam 24. The pawl 147 is resiliently maintained in engagement with the ratchet wheel 146 by the spring 155 mounted on the bracket 148. The cam roller 154 of the lever 151 in turn is resiliently maintained

in engagement with the cam 24 by the spring 156 which is connected at its upper end to the cross rod 116. The cam 24 is timed so that it will initiate the advance of the paper at about the end of the second third of the cycle, not completing the advance at the end of the cycle and consequently the advance of the paper strip will not be completed until about one-fourth of the new cycle has been completed.

After the advance of the paper and carbon strips has been completed, then in the cycle of operation, the movable printing platen 157 will be actuated by a hammer blow or impact on the outer face of the carbon strip 127 between the cross rods 14 and 15 in alinement with the stationary platen 58. The movable platen 157 is formed at the upper ends of the arms 158 and 159 journaled on the shaft 153. The arms 158 and 159 are connected to one another by the cross rod 160 which in the present instance extends beyond the outer face of the arm 159 and has connected thereto the upper free end of the impact spring 161 which is wrapped around the shaft 153 and has its other end tensed against the abutment 162. Extending from the outer face of the arm 159 is the bracket portion 163 at the outer end of which is formed the cam roller 164 maintained in engagement with the cam 25 by the impact spring 161. The cam 25 is so timed that it will release the arms 158 and 159 for an instantaneous blow to produce an impression on the paper strip. When the ticket 48 is positioned in the arms 59 and 60 and is an authorized ticket, its raised characters 112 will register with the stationary platen 58 in line with the movable platen 157 so that when the arms 159 and 160 are released by the cam 25 for actuation by the impact spring 161, the characters 112 will be impressed upon the paper strip 113.

Diagram

In the diagram of Fig. 25, an attempt is made to show the approximate successive steps of the machine during a cycle of operation. The cycle of the machine is assumed to start for the five operations depicted by the concentric circles 165, 166, 167, 168 and 169 at points on the radial line 170 and going in a clockwise direction as indicated by the arrow 171.

The outermost circle 165 depicts the actuation of the switch 28, the anchoring of the cross rod 35 by the cam 26 and in turn the release thereof; the circle 166 depicts the actuation of the movable platen 157 by the impact spring 161 and the restoration of the platen 157 to neutral position; the circle 167 depicts when the clearance of the female die 102 is effected, that is, when the depression of the projection 70, Fig. 19, clears the female die 102, the ensuing actuation of the punch 104 and the eventual restoration of the punch 104 to neutral position; the circle 168 depicts the initiation of the advance of the record strip 113 after the completion of an impression stroke by the platen 157, and after the end of the cycle and during the start of the next cycle, the subsequent completion of the advance of such record strip 113 before the next succeeding impression stroke of the platen 157 is effected; and the circle 169 depicts the actuation of the counter 108.

While excellent results have been achieved by the sequence of actuation here depicted, obviously they may be varied without departing from the general spirit of the invention. In the sequence depicted at the beginning of the cycle of the machine, the ticket 48 at a point in the radial line 170 actuates the cross rod 35 to actuate the projection 29 to close the microswitch 28, in turn to establish the electric circuit in the motor 17, thereupon after the cycle determined by the rotation of the shaft 21 has completed about one-third of its angular motion, at about the point 172 on the circle 165, the cam 26 will first actuate the lever 40, link 39 and arm 36 to maintain the cross rod 35 in depressed position and finally at the end of the cycle at about the point on the radial line 170

on the circle 165 the cam 26 will permit the lever 40 and therewith the cross rod 35 to be returned to neutral position. At about the same time that the cam 26 actuates the arm 40 into switch locking position, the printing platen 157 will be actuated by the impact spring 161 plotted as occurring at about the point 173 on the circle 166 whereupon, depicted by the arcuate line 174, the restoration of the platen 157 will ensue due to the cooperation of the cam 25 and the cam roller 164 of the arm 163, being completed at the end of the cycle plotted as occurring at about the point on the circle 166 intercepted by the radial line 170. In turn, about the same time that the platen 157 is actuated, the projection 70 will be depressed to clear the male punch head 103 plotted as occurring at about the point 175 on the circle 167, the actuation of the punch 104 by the eccentric 173 plotted as beginning at about the point 176 on the circle 167, the full punch stroke having been effected at about the point 177 on the circle 167 and the punch 104 again restored to neutral position at about the point in the circle 167 intercepted by the radial line 170. In turn, after the impression impact of the platen 157 has been completed, plotted as occurring at about the point 178 on the circle 168, the initiation of the advance of the record strip 113 will be effected, continuing through into the next cycle beyond the point on the circle 168 intercepted by the line 170, and being finally completed at about the point 179 on the circle 168 during the succeeding cycle of operation. Finally the movement of the counter 108 is plotted on the inner circle 169 to start at about the point 180 and being completed at about the point 181 in a time interval, although not necessarily so, starting before the impression impact of the platen 157 takes place and ending after the impression impact has been completed.

In general

The operative mechanisms of the machine are illustrated as mounted on two frames 3 and 11 which can be separated from one another primarily to facilitate inspection and repair of the machine. However, since the impact impression provoking spring 161 is mounted on the auxiliary frame 11 and the cam 25 for effecting its return is mounted in the frame 3, when the auxiliary frame 11 is withdrawn from the frame 3, the trip lever 182, Figs. 1, 2 and 3, will serve to anchor it in neutral position. This trip lever 182 is fulcrumed on the front face of the cross bar 12 having an upwardly extending projection 183 normally disposed in the path of the shoulder 184 at the lower end of the arm 159 when the auxiliary frame 11 is removed from the frame 3. When the projection 183 engages the shoulder 184 and maintains the arms 158 and 159 against the tension of the impact spring 161 in neutral position and the auxiliary frame 11 is introduced into the frame 3, the lower arm 185 of the trip lever 182 when striking the cam 186, see Figs. 1, 2 and 3, will actuate the lever 182 to release the shoulder 184 and permit the cam roller 164 to ride on the cam 25 so that the cam 25 will thereafter control the position of the arms 158 and 159.

The frame 11 is anchored to the frame 3 by the set screws 187 extending through the rear hangers 6 into frictional engagement with the cheek plates 9 and 10 of the frame 11.

From the foregoing, it will appear that the present invention has also provided an improved ticket or pass that can be used to good advantage in detecting and rejecting unauthorized passes.

In the claims the term "manipulating mechanism" will be used to apply either to the ticket punching mechanism, the record producing mechanism, the counter, or all three of the mechanisms.

It is obvious that various changes and modifications may be made to the details of construction without departing from the general spirit of the invention as set forth in the appended claims.

I claim:

1. In a ticket manipulating machine for receiving authorized tickets and recording the data formed thereon in raised characters, the combination of a main frame, a guide secured in said main frame for receiving and supporting an authorized ticket having a predetermined intact leading edge portion, a movable obstruction in said main frame and in the path of movement of said intact leading edge portion to be actuated by the same, a main drive in said main frame, a fixed platen in said main frame adjacent one side of the guide, an auxiliary frame slidably mounted in said main frame, a movable platen operatively mounted in said auxiliary frame adjacent the other side of the guide, an actuator for said movable platen mounted in said auxiliary frame, control means operatively connected to said main drive cooperating with said actuator to effect the actuation of said movable platen by said actuator, a recording medium mounted in said auxiliary frame interposed between the raised characters on the ticket and the movable platen to enable the actuation of said main drive to actuate said control means in turn to enable said actuator to actuate the movable platen to impinge the recording medium between the raised characters on the ticket and the movable platen to produce a record of the raised characters, an electric motor mounted in said main frame drivingly connected to said main drive, an electric circuit including an electric switch operatively connected to said motor, and means mounted in said main frame operatively connecting said movable obstruction to said switch to close said switch in turn to establish the current in said motor when said movable obstruction is actuated by said intact leading edge portion to operate said main drive.

2. In a ticket manipulating machine for receiving authorized tickets and recording the data formed thereon in raised characters, the combination of a main frame, a guide secured in said main frame for receiving and supporting an authorized ticket having a predetermined intact leading edge portion, a movable obstruction in said main frame and in the path of movement of said intact leading edge portion to be actuated by the same, a main drive in said main frame, a fixed platen in said main frame adjacent one side of the guide and engaging one side of the ticket, an auxiliary frame slidably mounted in said main frame, a movable platen operatively mounted in said auxiliary frame adjacent the other side of the guide to cooperate with said fixed platen, an actuator for said movable platen mounted in said auxiliary frame, control means operatively connected to said main drive cooperating with said actuator to effect the actuation of said movable platen by said actuator, a recording medium mounted in said auxiliary frame interposed between the raised characters on the ticket and the movable platen to enable the actuation of said main drive to actuate said control means in turn to enable said actuator to actuate the movable platen to impinge the recording medium between the raised characters on the ticket and the movable platen to produce a record of the raised characters, an electric motor mounted in said main frame drivingly connected to said main drive, an electric circuit including an electric switch operatively connected to said motor, and means mounted in said main frame operatively connecting said movable obstruction to said switch to close said switch in turn to establish the current in said motor when said movable obstruction is actuated by said intact leading edge portion to operate said main drive.

3. In an admission ticket manipulating machine, the combination of an authorized ticket having raised characters on the face thereof and a leading edge, said edge having a predetermined intact portion, a main frame, a guide in said main frame for receiving said ticket into a fully inserted position, said guide having two members extending therefrom to form a throat, an obstruction extending into said throat, said obstruction being mounted in said main frame in a selected position in the path of

5 10 15 20 25 30 35 40 45 50 55 60 65 70 75

movement of said intact edge portion, said obstruction when positioned in said selected position being movable into a second position upon engagement by said intact portion and the movement of the ticket to its fully inserted position, a drive shaft operatively mounted in said main frame, a cam on said drive shaft, a fixed platen mounted in said main frame adjacent one face of the ticket when inserted in said guide, an electric motor mounted in said main frame drivingly connected to said drive shaft, an electric circuit including an electric switch operatively connected to said motor, a cam bracket pivotally mounted in said main frame and operatively connecting said obstruction to said switch to close said switch in turn to establish the current in said motor when said obstruction is actuated by said intact portion, an auxiliary frame slidably mounted in said main frame, a movable platen operatively mounted in said auxiliary frame adjacent the other side of the ticket, an actuator operatively connected to said movable platen and mounted in said auxiliary frame including a lever and a cam roller on said lever in engagement with said cam when said auxiliary frame is positioned in said main frame, a recording medium mounted in said auxiliary frame interposed between the raised characters on said ticket and the movable platen to enable the actuation of said drive shaft when actuating said cam in turn to actuate said lever to release said actuator to actuate the movable platen to impinge the recording medium between the raised characters on the ticket and the movable platen to produce a record of the raised characters, said fixed platen backing up said ticket during the actuation of said movable platen.

4. The combination as set forth in claim 3 in which said switch has a contact making projection and said cam bracket has a cam face operatively associated with said projection to actuate said projection to close said switch when said movable obstruction is actuated.

5. In an admission ticket manipulating machine, the combination of an authorized ticket having a leading edge, said edge having a predetermined intact portion, a frame, a guide in said frame for receiving said ticket into a fully inserted position, said guide having two members extending therefrom to form a throat, an obstruction extending into said throat, said obstruction being mounted in said frame in a selected position in the path of movement of said intact portion, said obstruction when positioned in said selected position being movable into a second position upon engagement by said intact edge portion and the movement of the ticket to its fully inserted position, a drive shaft operatively mounted in said frame, an eccentric on said drive shaft, a punch lever pivotally mounted in said frame in operative engagement with said eccentric to be actuated thereby, a punch head on said lever adjacent the intact portion of the ticket in said guide, an electric motor mounted in said frame and drivingly connected to said drive shaft, an electric circuit including an electric switch operatively connected to said motor, said switch having a contact making projection, a cam bracket pivotally mounted in said frame operatively connected to said movable obstruction, said cam bracket having a cam face actuating said projection to close said switch in turn to establish the current to said motor when said movable obstruction is actuated by said intact portion, a cam on said drive shaft, and a linkage operatively connecting said cam to said cam bracket, said drive shaft when actuated actuating said eccentric to actuate said punch head to punch out the intact portion of said ticket and also actuating said cam to actuate said cam bracket and therewith to actuate and anchor said obstruction out of the path of movement of said punch head during a cycle of operation of the drive shaft.

6. In an admission ticket manipulating machine, the combination of an authorized ticket having a leading edge, said edge having a predetermined intact portion, a frame, a guide in said frame for receiving said ticket into

a fully inserted position, said guide having two members extending therefrom to form a throat, an obstruction extending into said throat, said obstruction being mounted in said frame in a selected position in the path of movement of said intact portion, said obstruction when positioned in said selected position being movable into a second position upon engagement by said intact edge portion and the movement of the ticket to its fully inserted position, a drive shaft operatively mounted in said frame, an electric motor mounted in said frame and drivingly connected to said drive shaft, an electric circuit connecting an electric switch operatively connected to said motor, said switch having a contact making projection, a cam bracket pivotally mounted in said frame operatively connected to said obstruction, said cam bracket having a cam face actuating said projection to close said switch in turn to establish the current to said motor when said obstruction is actuated by said intact portion, a cam on said drive shaft, a linkage operatively connecting said cam to said cam bracket, and a recording device operatively connected to said drive shaft, said drive shaft when actuated, actuating said cam to actuate said bracket and therewith actuate and anchor said obstruction during a cycle of operation of said drive shaft.

7. The combination as set forth in claim 6 in which said recording device includes a counter and a linkage operatively connecting said counter to said drive shaft.

8. The combination as set forth in claim 6 in which said recording device includes a punch head for punching out said intact portion, and an eccentric operatively connects said drive shaft to said punch head.

9. The combination as set forth in claim 6 in which said recording device includes a punch head for punching out said intact portion, a counter for recording the number of tickets passed through the machine, an eccentric operatively connecting said drive shaft to said punch head, and a linkage operatively connecting said drive shaft to said counter.

10. In an admission ticket manipulating machine, the combination of an authorized ticket having a leading edge, said edge having a predetermined intact portion, a main frame, a guide in said main frame for receiving said ticket into a fully inserted position, said guide having two members extending therefrom to form a throat, an obstruction extending into said throat, said obstruction being mounted in said main frame in a selected position in the path of movement of said intact edge portion, said obstruction when positioned in said selected position being movable into a second position upon engagement by said intact portion and the movement of the ticket to its fully inserted position, a drive shaft operatively mounted in said main frame, a cam on said drive shaft, an electric motor mounted in said main frame drivingly con-

nected to said drive shaft, an electric circuit including an electric switch operatively connected to said motor, a cam bracket pivotally mounted in said main frame operatively connecting said obstruction to said switch to close said switch in turn to establish the current in said motor when said obstruction is actuated by said intact portion, an auxiliary frame slidably mounted in said main frame, a recording device mounted in said auxiliary frame, and an actuator operatively connected to said recording device and mounted in said auxiliary frame including a lever and a cam lever on said lever in engagement with said cam to release said actuator to actuate said recording device when said auxiliary frame is positioned in said main frame.

15. The combination as set forth in claim 10 in which said ticket has raised characters and said recording device includes a movable platen operatively connected to said actuator, and a recording medium interposed between the raised characters of the ticket and the movable platen to enable the actuation of said movable platen to impinge the recording medium between said raised characters and the movable platen to produce a record of the raised characters.

20. 11. The combination as set forth in claim 10 in which said ticket has raised characters, said recording device includes a movable platen and a feed for a paper strip, said movable platen being operatively connected to said actuator, a recording medium connecting a strip of paper interposed between the raised characters and the movable platen to enable the actuating of said movable platen to impinge the recording medium between the raised characters and the movable platen to produce a record of the raised characters, a second cam on said drive shaft, and a second actuator operatively connected to said feed 25 mounted in said auxiliary frame including a second lever and a second cam roller on said second lever in engagement with said second cam to actuate said feed when said auxiliary frame is positioned in said main frame.

25. 12. The combination as set forth in claim 10 in which said ticket has raised characters, said recording device includes a movable platen and a feed for a paper strip, said movable platen being operatively connected to said actuator, a recording medium connecting a strip of paper interposed between the raised characters and the movable platen to enable the actuating of said movable platen to impinge the recording medium between the raised characters and the movable platen to produce a record of the raised characters, a second cam on said drive shaft, and a second actuator operatively connected to said feed 30 mounted in said auxiliary frame including a second lever and a second cam roller on said second lever in engagement with said second cam to actuate said feed when said auxiliary frame is positioned in said main frame.

30. 13. The combination as set forth in claim 10 in which said ticket has raised characters, said recording device includes a movable platen and a feed for a paper strip, said movable platen being operatively connected to said actuator, a recording medium connecting a strip of paper interposed between the raised characters and the movable platen to enable the actuating of said movable platen to impinge the recording medium between the raised characters and the movable platen to produce a record of the raised characters, a second cam on said drive shaft, and a second actuator operatively connected to said feed 35 mounted in said auxiliary frame including a second lever and a second cam roller on said second lever in engagement with said second cam to actuate said feed when said auxiliary frame is positioned in said main frame.
